UNITED STATES PATENT OFFICE.

WILLIAM NICHOLAS, OF NEW YORK, AND WILLIAM ACKERMAN, OF LARCHMONT, NEW YORK, ASSIGNEES, BY MESNE ASSIGNMENTS, TO UNITED STATES GRAPHOTYPE COMPANY, A CORPORATION OF NEW YORK.

JUSTIFYING MEANS FOR TYPE CASTING AND COMPOSING MACHINES.

1,310,207.

Specification of Letters Patent.

Patented July 15, 1919.

Application filed July 7, 1914. Serial No. 849,574.

To all whom it may concern:

Be it known that we, WILLIAM NICHOLAS, a subject of the King of Great Britain, residing at No. 222 West Twenty-third street, in the city of New York, county and State of New York, and WILLIAM ACKERMAN, a citizen of the United States, residing in the village of Larchmont, in the county of Westchester, in said State, have invented new and useful Improvements in Justifying Means for Type Casting and Composing Machines, fully described and represented in the following specification and the accompanying drawings, forming a part of the same.

Our invention relates to improvements in the means employed in type casting, composing and justifying machines for effecting sectional justifications within a standard or justified line of composed type. The object of the present invention more specifically stated is to improve and simplify the means to this end, which in its essential features comprises supplemental devices for controlling the usual actions of the mechanism employed in straight justification, so that the machine will vary its normal operations in order to effect such fractional justification, withholding the final operation in connection with the justification thereof until the final sectional justification has been effected, and then depositing the line into the galley containing the justified lines of composition.

Our invention therefore will be applicable to mechanism for casting type into justified lines, such as shown in our joint United States Patents Nos. 964,676 and 964,677, wherein controller devices are employed both for casting character type, and to determine the point in the operation of the associated parts for removing lines thus composed and justified into the galley.

Therefore, whether the tape device with perforations in predetermined combinations is employed in controlling the circuit making contacts for the above purposes, or whether separate selectors perform the same function, in the same general manner as illustrated in our joint United States Patent No. 964,679, in either of said forms of controllers a special trip selector would be employed in the usual manner preceding the justification selector in its passage through

the index head of the casting and justifying machine, for each of the sectional justifications required to make up a line, with this exception, that in our present device we do not require employment of a special signal for the multiple justification as has been used in all former devices designed for sectional justification.

Therefore our improvement is designed to simplify both the method and mechanism heretofore used to this end, and in the preferred form of our present invention we employ certain parts and devices heretofore used and employed in connection therewith together with devices for automatically operating those mechanisms to accomplish our present purposes. That is to say, heretofore, in both sectional and single justification, special controller signal devices have been required to effect the necessary connection between the justifier mechanism and the line pushing or galley feeding devices. In the preferred form of our present invention those same parts are now employed to accomplish both sectional and simple justification except that in the present invention we utilize action of the line itself, as it is fed into the galley to effect automatically the necessary connection between those parts to complete the multiple justification. That is, stated more particularly, by employing the mechanism heretofore used for connecting the line pushing slide with the justification slide so as to deliver the completed line into the galley, those parts may be normally operated and may remain disconnected one from the other during each sectional justification, and then connected finally to deliver the line into the galley when it has been set to its full length, *i. e.*, finally justified, effecting the necessary connections to operate the line pusher to deliver it into the galley.

We therefore employ the means illustrated in connection with the type casting machine illustrated in our said joint Patent No. 964,677, comprising the justifier slide and its actuating cam connections on the one end and the individual type and the line delivering slides on the other, the line delivering mechanisms comprising the usual galley pusher in the same manner as there illustrated.

Having reference to the drawings: Figure

1 is a partial plan view of the type casting machine to which the preferred form of our invention relates. Fig. 1^a a partial plan view of mechanism of parts shown in Fig. 1. 5 Fig. 2 is a sectional end view; Fig. 3 is a partial plan view showing the justifier slide; Fig. 4 is a sectional elevation on lines 4—4 of Fig. 3. Fig. 5 is a view similar to Fig. 4 showing the parts in a moved position; Figs. 6 and 7 are respective end and side elevations of a part shown in Fig. 5, 10 and Fig. 8 is a plan view of the line pusher mechanism.

Our invention in the preferred form illustrated is intended to apply to the mechanism described in our said joint Patent 964,677 wherein the driving shaft 1 which carried the several actuating cams relating to the different mechanisms of which the type casting machine is made up, among which as more intimately connected with our present mechanism are the pump actuating cam 5, the mold plunger actuating cam 10 and the justifying cam 15, the two former being 20 rigidly secured to said shaft while the latter is loosely mounted thereon and provided with a clutch mechanism through means of which it may be driven intermittently by said shaft, a special tripping mechanism being provided to be operated by a so-called trip controller selector device, of one form or another, as described in our said patents. 25

By means of the cam 5 the pump rod 6 through the action of its spring 7 is at the 30 proper timing made to operate the pump plunger to force the molten metal into the type mold when otherwise properly prepared for casting a type, and the mold plunger cam 10 will operate immediately thereafter to push the type thus cast out of the mold and into the galley mechanism, where the line of composition is assembled, one type at a time.

The pump mold cam 5 and the plunger cam 10 will therefore be rotated once for each type cast, or, stated conversely, at each rotation of the driving shaft and its attached cams, a type will be cast and forced by the type delivering plunger 11 in to the head portion of the galley 20.

As the foremost type of a line is fed into the galley mechanism, it is held by a suitable frictional or device of any convenient form, in an upright position as the line of type increases in length being held on the one side by the familiar rule 21 of thin sheet metal vertically supported by means which will operate to remove the rule when the line has been completed so as to be fed into the column that is being composed within the galley.

On the side of the line opposite the rule is the line pushing block 22, that also serves as a guide for the line of type being set, 65 which member with the rule forms a nar-

row passageway of a width corresponding to the point dimension of the type to be held therein.

The line pusher 22 which is carried across the passageway in which the type line is assembled, thereby forcing the line into the galley when it has been set to the full standard length, is fixed upon a sliding member 26, which is employed as in our said Patent No. 964,677 to furnish a suitable supporting 75 slide for the galley pushing block 22 said block and its guiding member being normally held by spring action in position for receiving the assembled line of type and preparatory to pushing it into the galley. 80

The slide 26 is operated through a connecting means presently to be referred to more in detail, by which it is operably united to the justifier slide 16 which it is understood always operates at the beginning 85 of each line of composition set by the machine. The actuating means, however, by which such connection is effected is the type delivering plunger 11, when it pushes the last type into the line, which when fully 90 justified is of the proper length to reach the parts to be operated thereby.

Thus, while the type are fed into the galley mechanism, one being so inserted at each rotation of the driving shaft of the casting 95 machine, the line pusher mechanism operates only once and that when the line has been completely justified to the standard length, or in other words once for each line thus composed. Therefore, inasmuch as the 100 justifier mechanism must be set previous to the casting of a line it is convenient to attach the line pusher actuating mechanism to the parts which are employed in setting the justifier mechanism. Hence, the form 105 of type casting machine to which the present form of our mechanism is applied, comprises a justifier slide 16 which is suitably mounted on the top plate of the machine frame and adapted to slide longitudinally, having at its 110 end a roll 16^a which is adapted to fit into a corresponding cam in the justifier cam 15; so that at each rotation thereof the slide 16 is reciprocated, to perform the functions heretofore described in connection with setting the justifier mechanism. 115

Immediately under the justifier slide 16 is the line pusher actuating slide 25 (see Figs. 3 and 4) which carries a vertical slideable clutch member 27, adapted to be forced 120 upwardly into an enlarged recess cut into the under side of the justifier slide 16 so that as said slide is carried forward by its cam it will also draw the line pusher slide 26 125 forward with it, and by reason of the vertical fulcrum lever 28 operably attached thereto, which at its upper arm is adapted to carry the line pusher forward to force the line into the galley. 130

Hence unless the clutch mechanism is elevated into locking position the justifier slide will perform its functions without disturbing the line pusher slide, and by providing 5 means whereby the clutch member is only carried into such operable position, when the line has been completely justified and inserted into the galley, it will be possible to employ the mechanism above referred to 10 in connection with multiple or sectional justification. We will therefore, at this point describe the means employed whereby this result is attained.

The clutch mechanism whereby the line 15 pusher slide may be connected with the justifier slide has been fully described in connection with our said joint Patent No. 964,677, and also the means for operating the clutch member has been therein fully set forth, and 20 therefore only certain features will be necessary to be referred to in this connection. A vertical pin 30 which is suitably guided in a bracket underneath the bed-plate is normally urged in the direction of the clutch 25 member 27 by means of a spiral spring 31 upon the stem of the pin, which presses against a collar suitably secured to said pin. The head 32 of the pin 30 provides a convenient shoulder for interposing a sliding, 30 device which will hold the pin out of engagement with the inclined portion 27^a of the clutch member, which, however, is adapted to be raised by action of said spring to operably unite the line pushing slides 26 to 35 the justifier slide 16. Hence, until it is desired to crowd the line into the galley, the pin 30 may be held out of engaging relationship with the clutch member as shown in Figs. 2, 4, 5, and 8, so that the justifier slide 40 may be operated as frequently as desired in setting the justifier parts to justify sectional 45 portions of a line without pushing them into the galley, thus permitting the type to advance between the rule and the galley pusher 50 until the line has been fully justified. Thereupon, when the line has been fully completed, by means which will next be described, the under slide 35 which is normally in position to hold the pin 30 out of engagement with the clutch member as above described, will be withdrawn, thereby permitting the connection to be made in the manner described between the justifier and line pusher slides.

Upon the top surface of the line pushing block and guide member 22, at the extreme end thereof is a slidable member 40, which is normally held against a stop 41 by means of a spring 42, being operably held thereon 55 by means of two screws within longitudinally disposed slots, at the respective ends thereof. The slidable member 40 is made in two parts, relatively adjustable longitudinally one to the other, the portion at the 60 end held in the manner indicated against the

stop peg 41, and the member 45 having projecting upwardly from its top portion a series of rectangular stops 46, into the interstices between adjacent stops thereof, is adapted to fit a tongue-like projection 51, 70 on the under side of a stop member 50, pivotally mounted upon a swivel post 52 loosely supported in a vertical bearing in the side bar 19 of the galley head. The member 50 thus pivotally attached to the swivel support 75 may be raised upon its pivoted bearing and shifted laterally simultaneously in making adjustable connections with the toothed member 45. Thus by lifting the free end of the stop member 50 its tongue 51 is withdrawn 80 from its position between the stops 46 of the member 45, in which it has been resting, and irrespective of the exact position of the side bar 19 may be located with reference to its position relative to the said 85 member 45, the finger 50 may be carried one notch either way by reason of its swivel support.

The toothed stops 46 are of a size and so placed to register pica em measurement so 90 that as the side bar 19, which is itself slidable in a path parallel to the member 45, is moved laterally to bring the tongue 51 of the stop member against successive stops 46 the galley measure will be widened by one pica 95 em for each successive step. In order to register fractional ems of registration to correspond with lines of such width, the toothed member 45 is adjustably attached to the stop slide 40 by means of the horizontal 100 screw 47 which is rotatably mounted in brackets 47^a upon the outer end of the member 40 and provided against longitudinal movement therein by means of a collar 47^b thereon adapted to run within a slotted 105 bearing in one of the brackets 47^a. The adjustable screw 47 has a knurled head and a threaded end 47^c entering a correspondingly threaded orifice in the lateral lug 45^e upon the member 45, which being held in the manner indicated against longitudinal thrust in either direction as it is turned will draw the toothed member 45 relatively toward or away from the slide 40 according to the direction of the screw 47 so that the member 110 45 may thus be moved to any fraction of an em carrying with it the stop member 50 when in position against the corresponding tooth 46.

The stop member 50 when thus in registering engagement with the tooth 46 is horizontally lowered to the level of the type line so as to be contacted by the forward member of the advancing line of type. Hence, by adjusting the side bar 19 and the toothed 120 member 45 with which it engages in the manner indicated to the desired pica width of line, it will readily be seen that when a line of corresponding measure is forced 125 against the stop member 50 by means of the 130

mold plunger 11, which is operated through the positive connections with the mold plunger cam 10. The stop member 50 will thus be forced upon the swivel support 52, carrying with it the slide 40, which through its connection by means of the adjusting screw 49 will likewise force the member 40 against the action of the spring to travel away from its stop pin 41 until the line is completely composed and fed into the galley by the plunger 11. Therefore, in order to employ this slide 40 to operate the connecting means between the line plunger slide and the justification slide only when the line has been fully composed and fed into the galley, it is necessary to have the stop member 50 normally resting at a position slightly shorter than the standard line to be justified thereby.

20 The means employed for utilizing the sliding action of the member 40 will now be described. At the side of the sliding member 40 there extends an arm 43 in the slot 44 which is adapted to pivot a thumb piece 61 which when thrown into engagement therewith operably connects the rock lever 60, to the slide 40 (see Figs. 1, 4 and 5) so that as the latter is moved in the manner described when the line has been fully set, the lever 60 is rocked upon its shaft 62. The shaft 62 is suitably mounted in brackets 63 upon the under side of the top plate 3, and when the lever 60 is actuated, swings the depending arm 65 also pinned thereto. Pivotally attached to the end of the lever 65 is a link 35 slidable on bracket 67 at the under side of the bed plate 4, the link member having at its outer end at right angles thereto an L extension 68, as viewed in plan. As the link 35 is reciprocated within its bearing by the lever 65, the L extension 68 is thereby brought immediately above the head 32 of the vertical pin 30, or carried out of the path of said head 32, owing to the direction in which the link 35 is carried by the lever arm 65 to which it is attached, and held in position by means of a spiral spring suitably supported upon the pivotal connection thereof and adapted to hold the link in operable contact with the block 67. It will be recalled that the vertical pin 30 when carried upwardly by its spring engages the clutch member 27 and thus operably locks together the justifier and line pushing slides, in order to insert the justified line into the galley. Therefore the L extension 68 of the sliding link 35 is of sufficient thickness, vertically considered, to hold the pin 30 out of position to throw the said clutch member into such locking engagement relatively to said slides, when the justifier slide 16 is carried forward by the action of the justifier cam 15 before the casting of the line next following that which has been justified un-

der the operation of our improved mechanism.

It will be recalled that the mold plunger 11, which is actuated by the cam 10 as it delivers into the galley the last type to complete the multiple justified line, by means of the opposite end thereof contacting the stop member 50, through the agency of the intervening slide bar 19 and its connections, in this manner vibrates the lever arm 65 and reciprocates the link slide 68 both in and out of contacting position relatively to the head of the clutch vertical lift pin 30 which effects the clutching of the line pushing slide to the justifier slide, which is driven by the justifier cam 15. Hence inasmuch as both of said cams are driven by the the same shaft 1, by suitably timing the operations thereof, the link slide 68 may be withdrawn by operation of the cam 10, in the manner described, previously to the arrival of the justifier slide at the position in which the toothed recess 29 therein is over the clutch member 27, so that the latter will be forced upwardly into said recess and the line pushing slide 25 in which it is vertically guided will accordingly be carried forward with the justifier slide 16. Thus means are provided whereby the fully justified line of type effects the necessary connections for its insertion into the galley, and for the reason that such connections are not made until the full line has been composed, the justifier slide is available for the purposes of setting the other or normal justifier parts for the successive sectional justifications of the line, during which incomplete multiple justifications the tripping mechanism is also free to operate as often as required, without delivering the line to the galley, until as thus provided the final justification has been made.

In order to facilitate the withdrawal of the link slide 68 from the head 32 of the vertical pin 30, which is by action of the spring 31 at all times urged in the direction of the under surface of the plate 4 against which said link is slidably held, the extension L 68, as shown in Fig. 3, is reduced in its vertical cross-section so that when the tooth of the clutch member 27 is contacted with the forward portion 33 of the under side of the justifier slide 16, the head pin 30 is thereby pressed sufficiently to relieve the link slide of all frictional pressure of the head 32 of said pin as a result of the action of its spring. Hence, as the link slide 35 is withdrawn, and likewise reinserted under the head of the vertical spring pin while the forward face 33 of the justifier slide is pressing upon the clutch member and its supporting pin 30, as shown in Fig. 3, the objectionable frictional resistance that would otherwise interfere with the employment of an actuating element

comprising a yielding line of type is removed.

However, inasmuch as the clutch member 27 must be held out of engagement with the toothed recess 29 of the justifier slide by the interposition of the L extension 68 of the link slide 35 as the justifier slide goes forward during the setting of the parts for the partial justifications, the line not yet being ready to be advanced to the galley, unless provision is made to the contrary the clutch member would be carried up into engagement with the toothed recess 29 while the L extension of the linked slide 35 is under the head of the vertical pin 30. To obviate this difficulty the rearward under surface 34 of the justifier slide adjacent the engaging edge of the toothed recess 29 is elevated to an extent slightly in excess of 20 the distance the pin 30 is allowed to rise by reason of the diminution of the height of the said extension 68 of the link slide. Hence when the slide 35 is under the head of the vertical pin the justifier will pass idly over the clutch locking member 27, and when the slide is to be inserted under the head of the pin or withdrawn therefrom it may be accomplished without undue frictional resistance to prevent its free operation to that end.

Having described our invention, what we claim is:

1. In a type casting and composing machine, record controlled means for forming lines therein and for pushing said line into a galley; means for rendering inoperative said line pushing means until a line of predetermined length has been forced in position therein to be pushed into the galley; and mechanical means comprising a transverse 35 stop finger adapted to be contacted by an advancing line of predetermined length; and means including said stop finger for operating said line pushing means.

2. In a type casting and composing machine, means for justifying lines in multiple

sections within a galley mechanism provided in connection therewith, said justifying means comprising a cam actuated slide; means for advancing the line longitudinally thereof into the galley head by operation of 50 a type plunger; a line pusher for transferring composed lines laterally into the galley, actuated by a slidable bar adjacent said cam actuated slide; means for operably connecting said bar and slide, comprising a sliding member longitudinally disposed upon said line pusher; means for actuating the sliding member comprising a transverse stop finger adjustably attached thereto and adapted to be contacted by the advancing line of type 55 when fully justified; and means whereby said sliding member actuates said clutch member to operate the line pusher by said line justifying means.

3. In a type casting and composing machine, means for justifying standard lines in multiple sections, said justifying means comprising a cam actuated slide; means for advancing partially justified lines into the galley mechanism thereof; a line pusher for 60 transferring composed lines to the said galley, comprising clutching means for operably attaching said line pusher to said cam actuated slide; mechanism for actuating said clutching means comprising a yielding member, a clutch member, and a slide, said slide being adapted normally to hold said clutch member out of engagement; and means actuated by a fully justified line for removing said slide to permit said clutching mechanism to operate to permit the justifying 65 means to push said line into the galley.

In testimony whereof, we have hereunto set our hands in the presence of two subscribing witnesses.

WILLIAM NICHOLAS.
WILLIAM ACKERMAN.
